UNITED STATES PATENT OFFICE.

GEORGE HERBERT COOPER, OF NEW WESTMINSTER, BRITISH COLUMBIA,
CANADA.

STEAM-BOILER.

SPECIFICATION forming part of Letters Patent No. 339,383, dated April 6, 1886.

Application filed August 20, 1884. Serial No. 111,049. (No model.)

To all whom it may concern:

Be it known that I, GEORGE HERBERT COOPER, of New Westminster, British Columbia, Dominion of Canada, have invented a new and Improved Steam-Boiler, of which the following is a full, clear, and exact description.

The object of my invention is to construct a boiler with extensive heating-surface and capable of standing high pressure.

It consists in a series of water boxes or sections, of flat and narrow form, connected a short distance apart, the space between the several boxes forming the flues, as hereinafter described and claimed.

Reference is to be had to the accompanying drawings, forming part of this specification, in which similar letters of reference indicate corresponding parts in both the figures.

Figure 1 is a sectional side elevation of a boiler of the improved construction, and Fig. 2 is a transverse section of the same through the fire-box.

The water boxes or sections *a* are formed of sheets of iron or steel, connected by short bolts and retained apart a short distance by strips *b* at the edges, so as to form boxes of flat form, the space between the sides being about an inch. Any suitable number of these boxes are placed side by side, with narrow spaces between and connected by braces, so as to form flues that terminate in a smoke box, *d*, at the rear end of the boiler.

Between the sections *a*, a short distance below the water-line, rods or bars *j* are placed, which extend from the front plate to the smoke-box, and may be bent at the inner ends of the sections to extend upward to the top of the sections, as at *j'*. These rods or bars are designed to fit loosely between the sections, and are intended to prevent the flame from rising too high between the sections.

The interior boxes, *a*, are cut out at the front end to form a fire box, *c*, the sides of which are formed by the outside boxes, and the front of the boiler is closed by a plate that

has an opening to the fire-box, closed by a door. The top and bottom may be covered by plates or by brick-work. In the upper edges of these boxes *a* recesses are formed alternately, to allow connection of the steam-pipes *e*, that in turn are connected by a pipe, *f*, to a steam-dome, *g*, and a feed-water pipe is connected in the same manner at *h*.

A safety-valve may be connected to the boiler directly, or placed on the dome, as shown. A pressure-gage, *i*, is connected at the front.

The advantages of this construction are, that the boiler has extensive heating-surface compared to the body of water, and there will be consequently economy of fuel. The boiler is also capable of bearing high pressure, and as each box or section will contain but a small amount of steam an explosion would be attended with only light results.

I am aware that partitions have been used between the tubes of tubular sectional boilers to form circulating flues and to limit the ascent of the products of combustion, and therefore do not claim, broadly, such partitions.

Having thus described my invention, I claim as new and desire to secure by Letters Patent—

1. In a steam-boiler composed of a series of vertical sections, as *a*, the alternate sections recessed, as at *e*, substantially as shown and described, whereby the steam-pipes connecting the said sections with the steam-dome may be connected at the sides of the sections, as set forth.

2. In a sectional steam-boiler composed of a series of vertical flat box-like sections, as *a*, the combination, with said sections, of the bars *j*, placed longitudinally in the spaces between the sections below the water-line, and extended upward at the rear of the sections, as at *j'*, substantially as shown and described.

GEORGE HERBERT COOPER.
